UNITED STATES PATENT OFFICE.

ELDON H. MITCHAM, OF CHARITON, IOWA.

ROTARY-VALVE STRUCTURE.

Application filed April 7, 1926. Serial No. 100,326.

My invention relates to rotary valve structures for controlling fuel intake and gas exhaust of internal combustion engines.

More particularly, it is my object to provide a rotary valve structure of very simple and inexpensive construction, having novel features in the details of its mounting, operation and cooling means.

With these and other objects in view, my invention consists in the construction, arrangement and combination of the various parts of my device, whereby the objects contemplated are attained, as hereinafter more fully set forth, pointed out in my claims, and illustrated in the accompanying drawings, in which:

Figure 1 is a vertical, sectional view through the upper part of an internal combustion engine equipped with a rotary valve structure embodying my invention.

Figure 2 is a detail, sectional view taken on the line 2—2 of Figure 1; and

Figure 3 is a detail, sectional view taken on the line 3—3 of Figure 1.

In the accompanying drawings wherein my invention is illustrated, I have employed the reference numeral 10 to indicate generally the cylinders of an internal combustion engine. The engine block 11 is provided with the upper water passages 12 for cooling purposes.

In each cylinder, is a piston 13 having a connecting rod 14, which is operatively connected with the usual crank shaft 15.

The engine block 11 has the detachable head 16 provided with passages 17 communicating with the passages 12 and also provided with a central, longitudinally arranged casing 18, shown particularly in Figures 1 and 2, for my rotary valve.

The valve casing 18 terminates at each end substantially short of the end of the engine head 16, as shown for instance in Figure 1. It may be also noted that at each end, the valve casing 18 has a bell flange, these flanges being indicated at 19 and 20 in Figure 1. The bell flanges 19 and 20 are interiorly screw-threaded. The lower part of the valve casing 18 communicates with the upper part of each cylinder 10 by means of a suitable opening or passage 21, shown for instance in Figures 1 and 2.

Connected with the upper part of the valve casing 18, a little on one side from vertical center, is the intake manifold 22 and

connected with the upper part of said casing along the other side of the vertical center is the exhaust manifold 23.

The head 16 is formed with short passages 24 and 25 for affording communication between the casing 18 and the intake and exhaust manifolds. At the ends of the head 16 are screw-threaded closure plugs 26 and 27, as shown in Figure 1, which are of sufficient size for the purpose.

Received within the casing 18 is a rotary valve 28, comprising a tube, which at the rear end projects beyond the main bore of the casing 18 and at its forward end projects entirely beyond the casing 18, and the bell flange 20, and has the gear 29 keyed thereon, and beyond that the forwardly extending portion 30.

At the rear end of the casing 18, a packing gland 31 surrounds the end of the shaft 28 and is screwed into the bell flange 19 and serves to hold the packing 32 in place. Near the front end of the casing 18, a similar packing gland 33 is screwed into the bell flange 20 and serves to hold the packing 34 in place for making a tight joint.

It will be remembered that a portion of the valve 28 projects beyond the gland 33 and has keyed thereon the gear 29.

A housing 33^a is bolted or otherwise secured, to the engine head 16 and has formed on the interior thereof, an annular stop rib 34^a, shown in Figure 1, and a packing gland 35 also shown in Figure 1, is screwed into the front part of the housing 33^a for holding packing 36 between it and the rib 34^a.

At the lower front part of the engine, a gear 37 is mounted on a counter shaft 38 in mesh with a spur gear 39 on the crank shaft 15. The gear 29 is a sprocket gear and in line therewith on the shaft 38 is another sprocket 40. A chain 41 travels on the sprockets 29 and 40. Thus motion is transmitted from the crank shaft 15 through the gears 39 and 37 to the shaft 38 and from that shaft through the sprockets 38 and 29 and the chain 41 to the valve 28. The housing 33^a extends down as at 46 and covers the gears, sprockets and chain.

It may be mentioned in this connection that the reduction is four to one.

The end thrust of the rotary valve is taken care of by the packing nut 33 and the annular rib 34^a against which the gear 29 abuts.

At each end of the shaft 28, a space 42 is afforded for water circulation. At the front housing 33^a, the space 42 is connected by means of the passage 43 with the radiator and at the rear end of the head 16, the space 42 is connected with the usual water jacket space 12.

It thus appears that water can flow through the hollow, tubular valve 28 for cooling it.

I have provided suitable oiling passages 44 for affording means for properly lubricating the valve 28.

It will, of course, be understood that the passages 44 are connected with a suitable source of oil supply.

While the structure of my device may vary considerably, I have in the present drawings shown the respective passages 24 and 25 to be opposite each other, and where this structure is employed, I provide one intake and exhaust passage in the valve for each cylinder 13.

This exhaust passage is formed by means of a flattened tube 45 extending diametrically across the valve.

It will be understood that the series of fuel passage tubes 45 for the different cylinders are arranged at proper angles to each other according to the desired timing of the device.

In the practical use of my improved rotary valve, it will be seen that the shaft 28 is rotated from the crank shaft at the rate of one to four. Referring for instance to Figure 3, it will be noted that the passage 45 is just midway between exhaust and intake positions. A little further clockwise movement of the shaft 28 will bring the passage 45 to intake position. After intake, then for the next one-eighth revolution of the valve, there occurs the compression stroke of the motor, and during the third one-eighth revolution occurs the firing stroke of the motor. Another one-eighth revolution will bring the valve to exhaust position.

Thus as here shown, the valve makes one revolution to four revolutions of the crank shaft and to two complete cycles of operation of the engine.

It will be noted that I have provided a very simple and inexpensive manner of mounting the valve in the casing and provided for the water flow through it and for providing the sprocket gear 29 at the front end between two portions of the valve, which are suitably mounted in bearings.

Furthermore, the sprocket gear 29 is protected against water in the water jackets by the shoulder 34^a, packing 36 and gland 35 on the one side, and the bell flange 20, which

is integral with the head 16 and with the casing 18 on the other side.

There is thus provided a very efficient valve structure.

One great problem in structures of this kind is to afford proper cooling in order to take care of the problems of expansion and contraction, and this problem is solved by the construction heretofore described. It may here be mentioned that the tube 28 could be in communication with the oiling system of the car for cooling it or it could be open to the atmosphere at each end whereby the current of air created by the fan of the engine would pass therethrough for cooling the valve.

I have also afforded what I believe to be a novel and desirable structure in the manner of imparting rotation from the crank shaft to the valve, particularly in the arrangement of the sprocket gear on the valve in the manner described.

I claim as my invention:

1. In a structure of the class described, an engine block having cylinders, a head supported on said block, a rotary tubular valve in said head, packing and packing glands in said head and surrounding said valve adjacent the ends thereof, one end of said valve projecting beyond its packing gland and having a sprocket secured thereon and having beyond said sprocket an extending portion, a housing secured to said head and covering said sprocket and extending portion, an annular rib on the interior of said housing surrounding said extending portion, a packing and a packing gland in said annular rib, and water jacket spaces in said head and said housing at the ends of said valve whereby water may circulate through the valve from one of said spaces to the other.

2. A rotary valve construction comprising a head adapted to be secured to the block of an engine, a rotary tubular valve therein, packing means between the valve and the head adjacent each end thereof, one end of said valve extending beyond the packing means, a driving sprocket secured thereon, a housing for said extending portion, packing means between said housing and the extending portion, an annular rib in said housing, plugs in said housing and said head at each end of the valve whereby access may be had to the packing means and said valve may be removed when the plugs are removed, one of said packing means and said annular rib serving as end thrust bearings for said sprocket.

Des Moines, Iowa, March 19, 1926.

ELDON H. MITCHAM.
